COMBINED FRYPAN AND COVER

Katharina Siren and Andrew Oskar Siren, both of 3436
15th St. SE., Calgary, Alberta, Canada

Filed Feb. 8, 1971, Ser. No. 113,797

Term of patent 14 years

Int. Cl. D7—02

U.S. Cl. D7—95

FIG. 1

FIG. 2

FIG. 3

FIG. 4

FIG. 1 is a side elevational view of a combined frypan and cover, showing our new design;

FIG. 2 is a top plan view thereof;

FIG. 3 is a top plan view of the frypan with the cover removed; and

FIG. 4 is a bottom plan view of the combined frypan and cover.

We claim:

The ornamental design for a combined frypan and cover, as shown and described.
